UNITED STATES PATENT OFFICE.

ROBERT C. FOLGER, OF ALBANY, NEW YORK.

DESIGN FOR A COLLAR.

SPECIFICATION forming part of Design No. 26,534, dated January 12, 1897.

Application filed December 3, 1896. Serial No. 614,362. Term of patent 31 years.

To all whom it may concern:

Be it known that I, ROBERT C. FOLGER, a citizen of the United States, residing at Albany, in the county of Albany and State of New York, have invented a certain new and useful Design for Collars; and I do declare the following to be a full, clear, and exact description of the invention, such as will enable others skilled in the art to which it appertains to make and use the same, reference being had to the accompanying drawings, and to the letters of reference marked thereon, which form a part of this specification.

The reference letter a represents the neck-band portion, which is given a height substantially equal to that of an ordinary waist-collar and is adapted to be inclosed within and rise above the top of the latter. The ends b are made rectangular and of a width equal to that of the band a. Two horizontal buttonholes, placed one above the other, are formed in the opposite ends of the band.

d represents the flap of the collar, which is attached to the top edge d' of the band and is designed to stand out at right angles thereto. This flap is given the general outline of a perfect square, excepting at the point over the buttonholes, where a square place e is cut out to form two front corners f. This rectangular flap d is so arranged on the collar-band a that the main corners h and i will be located at the back and sides of the neck-opening j, the point h lying exactly behind the opening j and the points g and i on the right and left thereof, respectively.

What I claim as new, and desire to secure by Letters Patent, is—

The design for a collar substantially as herein shown and described.

In witness whereof I affix my signature in presence of two witnesses.

ROBERT C. FOLGER.
